UNITED STATES PATENT OFFICE

ROYCE L. BEERS, OF DETROIT, MICHIGAN, ASSIGNOR TO DETROIT STOKER COMPANY,
OF DETROIT, MICHIGAN, A CORPORATION OF MICHIGAN

UNDERFEED STOKER

Application filed January 19, 1925, Serial No. 3,521. Renewed October 2, 1929.

This invention relates generally to stokers having mechanism for feeding fuel into and through the usual retorts and consists of novel and efficient driving mechanism in which provision is made exteriorly of the furnace for the adjustment of such feeding mechanism for regulating the movement of fuel therethrough.

In the accompanying drawings:

10 Figure 1 is a vertical central longitudinal section through a stoker embodying my invention;

15 Figure 2 is a cross sectional view taken on the line 2—2 of Figure 1;

20 Figure 3 is a side elevation of one of the sectional bearings;

Figure 4 is an end elevation thereof;

25 Figure 5 is a side elevation of one of the pitman rods and showing the links connected thereto;

Figure 6 is a top plan view of the construction shown in Figure 5;

30 Figure 7 is a front elevation of the adjusting block and collar that are adapted to be mounted upon one of the pitman rods;

Figure 8 is an end view of the construction shown in Figure 7;

35 Figure 9 is a detail view of one of the rods carried by the pitman rods;

Figure 10 is a detail side elevation of the rear adjusting block;

Figure 11 is an end elevation of the block shown in Figure 10;

40 Figure 12 is a detail view of the rear retaining pin;

Figure 13 is a detail of the forward retaining pin;

Figure 14 is a detail view of the pin sliding in the pitman rod;

45 Figure 15 is a top plan view of one of the rams.

In the drawings, 1 designates a series of laterally spaced retorts into which green fuel is fed from suitable hoppers 2 supported in front of the furnace upon casings 3 in alignment with the retorts 1. The green fuel may be supplied by any suitable means (not shown) to the hoppers and fed into the retorts by suitable rams 4 mounted in the casings 3. These rams are reciprocated by pit-

man rods 5 having substantially rectangular shaped heads 6 at their outer ends through which relatively long rods 7 preferably extend. These rods project above and below the crank portions 8 of a rotary shaft 9 in front of the furnace and support suitable blocks 10. Loosely mounted on the crank portions 8 of this shaft are sectional bearings 11 which are preferably sleeved upon the rods 7 between the heads 6 and the blocks 10. The halves of these bearings may be secured together by bolts or the like 11'. Any suitable means such as the nuts 12 threadedly engaging the inner ends of the rods 7 may be used for securing the rods to the pitman heads 6, while suitable inverted L-shaped pins 13 are preferably used to hold the blocks 10 on the rods 7. As shown, these pins 13 preferably extend through aligned openings 14 in the blocks 10 and are engageable with suitable openings 15 spaced longitudinally of the rods 7. Thus, the blocks 10 may be adjusted longitudinally of the rods 7 to provide variable lost motion for changing the positions to which the rams may be moved at the end of their backward strokes. If desired, the rams 4 may be adjusted to their advanced position where they act as cut-offs for the hoppers 2. To facilitate such adjustment, the blocks 10 are first moved to the outermost position on the rods 7, after which rotation of the crank shaft 9 will push the rams 4 forward, but will not return the same as the clearance or lost motion is equal to the full stroke. Inasmuch as there are separate connections between each ram and the crank shaft 9, it is readily apparent that any one of the rams may be left in cut-off position while the other rams are operated.

For advancing the fuel longitudinally of the retorts, I have provided suitable wedge-shaped pusher blocks 17 mounted on pusher bars 18 having short extensions 21 extending through the heads 22 of the rams 4 and connected at their rear ends to parallel links 23 which in turn are connected to the pitman rods 5. These links preferably extend upwardly upon opposite sides of the pitman rods 5 and are connected at their free ends 100

by suitable pins 24 that preferably extend through longitudinally extending slots 25 in said rods. Slidably mounted in the slots 25 in the pitman rods 5, preferably in advance of the pins 24, are suitable blocks 26 having vertical openings 27 adapted to register with spaced vertically aligned openings 28 in the pitman rods 5. As shown, the blocks 26 are guided in the slots 25 by inverted substantially U-shaped collars 29 that straddle the rods 5 and are connected by means of suitable screws 30 to the opposite sides of the blocks. For holding the blocks 26 in adjusted position, I preferably provide suitable pins 31 that are engageable with the openings 32, 28 and 27 respectively in the collars 29, rods 5 and blocks 26. Thus, the blocks may be adjusted longitudinally of the pitman rods 5 to provide variable lost motion for changing the positions to which the pusher blocks 17 may be moved at the end of their backward strokes. Inasmuch as the links 23 are connected to the pitman rods 5, it will be readily apparent that the positions to which the pusher blocks 18 may be moved at the end of the backward strokes of the rams may be correspondingly changed by adjusting the blocks 10. If desired, both the rams and pusher blocks of any retort may be rendered inoperative while the others are operating by adjusting the blocks 10 to the rear ends of the rods 7 to permit the bearings 11 to slide freely upon the rods 7. Moreover, the length of the slots 25 in the pitman rods 5 is such that the blocks 26 may be adjusted forwardly a sufficient distance to permit the pins 24 to travel freely in the slots 25 without actuating the pusher bars 18; thus the pusher blocks 17 may be rendered inoperative by adjusting either the blocks 10 or the blocks 26. Inasmuch as both the blocks 10 and 26 are positioned exteriorly of the furnace, the supply of fuel and the advancement thereof in the retorts may be conveniently regulated as desired while the stoker is operating for obtaining the proper fuel bed.

What I claim as my invention is:

1. In a stoker, the combination with a retort, a ram for feeding fuel into the retort, and a pusher block for advancing fuel longitudinally of the retort, of a rotary drive shaft, a pitman rod for reciprocating said ram operatively connected to said shaft, a bar for actuating said pusher block, a link connected to said bar, a pin carried by the link slidably engaging said pitman rod, and means adjustable longitudinally of the pitman rod adapted to be engaged by said pin for regulating the positions to which said pusher block may be moved at the end of the backward strokes of the ram.

2. In a stoker, the combination with a retort, a ram for feeding fuel into the retort, and a pusher block for advancing fuel longi-

tudinally of the retort, of a rotary drive shaft, a pitman rod for reciprocating said ram operatively connected to said shaft, a bar for actuating said pusher block, an extension for the bar movable through the ram, and a link for actuating the bar connected to the extension and pitman rod. 70

3. In a stoker, the combination with a retort, and a ram for feeding fuel into the retort, of driving mechanism for the ram including a rotary crank shaft, a pitman rod connected to the ram having a head, spaced rods carried by the head, a block adjustably mounted on the spaced rods, a bearing loosely mounted on a crank portion of said shaft 75 slidably mounted on said spaced rods between the head of the pitman rod and said block, and removable means engageable with said spaced rods for holding said block in adjusted position. 80

4. In a stoker, the combination with a retort, a ram for feeding fuel into the retort, and a pusher bar for advancing fuel through the retort, of a rotary crank shaft, a pitman rod for reciprocating said ram operatively 90 connected to said shaft, a link connected to said pusher bar, a pin carried by said link slidably engaging a slot in said pitman rod, and means adjustable longitudinally of said pitman rod adapted to be engaged by said 95 pin for regulating the extent of movement of said pusher bar.

5. In a stoker the combination with a retort and a ram for feeding fuel thereinto, of a drive shaft, a pitman rod connecting the drive shaft to the ram and a pusher within the retort adjustably connected to the pitman rod in the line of thrust thereof and intermediate said shaft and ram. 100

6. In a stoker mechanism of the class described, the combination with a retort and a ram for feeding fuel thereinto, of a drive shaft, a pitman rod connecting said shaft to said ram, a pusher within the retort and means connected thereto and extending without the retort for adjustably connecting said pusher to said pitman rod in substantially the line of thrust thereof and at a point intermediate the shaft and ram. 105

7. In a stoker mechanism of the class described, the combination with a retort, of a ram member for feeding fuel thereinto, an operating member for reciprocating the ram, a pitman directly connecting said members and exerting an axial thrust upon the ram, a pusher within the retort and an adjustable connection between the pusher and pitman in the line of thrust of the latter and exteriorly of the ram. 115 120

In testimony whereof I affix my signature. 125
